Primary Examiner — George D. Kirschbaum*Assistant Examiner* — Lillian Windham(74) *Attorney, Agent, or Firm* — Paratus Law Group,
PLLC(57) **CLAIM**

The ornamental design for a whistle, as shown and described.

DESCRIPTION

FIG. 1 is a front, top, and right sides perspective view of a whistle, showing our new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a cross-sectional view taken along line 8-8 shown in FIG. 2;

FIG. 9 is an exploded view thereof; and,

FIG. 10 is a reference view showing the whistle in use.
The evenly spaced broken lines shown in FIG. 10 depict
environment and form no part of the claimed design.**1 Claim, 4 Drawing Sheets****FIG. 1****FIG. 2****FIG. 3****FIG. 4**
